UNITED STATES PATENT OFFICE.

JOHN THOMSON, OF NEW YORK, N. Y.

ELECTRIC ZINC-FURNACE WITH INTEGRAL CONDENSER.

1,090,427.

Specification of Letters Patent. Patented Mar. 17, 1914.

Application filed January 2, 1913. Serial No. 739,787.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being made to the accompanying drawings, forming a part hereof.

This invention relates to the metallurgy of zinc and the object thereof is to produce metallic zinc by the reduction of oxid of zinc (ZnO) by carbon (C); also to condense the zinc to liquid metal as and when and at the rate it is produced. The heat necessary for decomposing the ZnO and C is derived from an electric current passed through a "resistor".

The invention resides in particular means designed to accomplish the objects above stated in a practicable and effective manner and upon an economical commercial scale of operation.

The resistor above mentioned is comprised in a bed of carbon, usually made of coke, which is disposed upon an open refractory grating, formed of bars or plates. The size and shape of the carbon pieces as well as the depth, width and length of the resistor bed may be variously modified to obtain any desired electrical resistance and intensity of current, which is brought to the two ends of the resistor by blocks or plates of amorphous carbon or graphite, situated at and within the ends of the reaction chamber, that is, the resistor is interpolated between the two terminals.

The reaction chamber of the furnace in which the resistor is contained is made of sufficient depth to receive a shallow charge, the latter being placed directly upon and sustained by the resistor. The "charge" is comprised of either a mixture or alternate layers of oxid of zinc and of carbon in preferably the exact relative proportions to effect, when suitably heated, practically their complete reduction and evolution in the forms of zinc fume (Zn) and monoxide of carbon (CO); that is to say, any unevolvable or inert residual matter will be of nominal or even negligible amount.

As already intimated, the electric energy

is transformed into caloric energy in the resistor bed, and the heat thus generated, if the temperature is adequate, effects the decomposition of the superimposed mass, the following representative chemical reaction ensuing:

In general terms that portion of the base of the furnace immediately beneath the resistor is utilized to condense the zinc fume, to collect the liquid metal and to evacuate the residual gases. In other words, the underlying section contiguous to the reaction chamber is caused to serve as the "condenser". Means are afforded for obtaining and maintaining adequate intimacy of contact between the resistor and the charge, whereby to produce a uniform absorption of heat units and a correspondingly effective evolution of volatilized products. The manner of making electrical contact between the carbon terminals and the resistor and the method of connecting the said terminals to the bus-bars or main line cables are matters of importance; these details have been improved. When oxid of zinc of a low grade of commercial purity and carbon in the usual form of coke or coal are employed, it has been found desirable to so dispose and support the bed resistor as to increase the period of its effective endurance and to also facilitate its speedy substitution when required. The thermal efficiency of the furnace, by reduction of heat losses due to radiation, is improved and finally a design is provided whereby the reaction may be caused to proceed at or about or even slightly below atmospheric pressure.

When the $ZnO + C$ reaction is employed to primarily produce zinc fume from its oxid the resulting classical formula,

may not be precisely realized, nor is it at all likely that it is perfectly realizable in a commercial furnace operation, for there are practically always present sensible quantities of air and water which are both entrained and in chemical combination. This is especially the case if the carbon is in the form of ordinary coke, also if the oxid of zinc is a commercial oxid of zinc and if it has not been calcined and compressed. These materials

are cellular and hydroscopic; therefore, as ordinarily employed, the reacting materials contain appreciable quantities of both air and H_2O , which are pernicious oxidizing elements.

It is well established that the $ZnO + C$ reaction begins and slowly proceeds at or about $1900^{\circ} F.$, progressively increasing and becoming quite active at and above $2200^{\circ} F.$

10 Hence it appears that a certain relation exists between the formation temperature of CO and the initial stage of the reaction, exemplified by the classical formula. It is also well established that zinc metal when 15 fused will remain liquid up to or about the temperature of $1710^{\circ} F.$, but it then, if supported with the latent heat of volatilization, becomes a cloud-like or gaseous fume, that is, if "boiled" in the atmosphere and hence 20 visually observable. This is also the basis usually accepted as applicable to zinc-fume when produced by a chemical reaction.

When zinc-fume is evolved the pernicious oxidizing element CO_2 may also be present, 25 the effect of which would ordinarily be to precipitate a portion of the fume in the form of "blue-powder" or as "schnelz" or in some combination of both. But if the CO_2 , 30 mingles with the zinc-fume and CO in the presence of carbon (C) and all are subjected to an adequately high reacting temperature, then there will be a secondary, reciprocal or interreaction which virtually acts to "cleanse" such portion of the zinc-fume as 35 may have been oxidized by the CO_2 . Ordinarily the quantity of CO_2 will be relatively small and as its density is also greater than that of CO it is highly diluted. As an oxidizing agent both time and temperature are 40 doubtless functions of the action.

Having regard then to the foregoing general outlines and to these expressions of the controlling principles, the several coördinating features of the invention will now be 45 described in detail, reference being had to the illustrated example or embodiment thereof shown in the accompanying drawings in which—

Figure 1 is a transverse center section, 50 viewed as A, of Fig. 2, of a furnace denoting a realization of the invention the resistor having been removed from the right half of the furnace. Fig. 2 is a longitudinal center section, viewed as B or B' of Fig. 1. Fig. 55 3 is a transverse center section, viewed as C, of Fig. 4, indicating a realization of the invention in another form of apparatus, the resistor being indicated by the dotted line. Fig. 4 is a longitudinal center section, 60 viewed as D or D' of Fig. 3. Fig. 5 is a partial horizontal section and plan, viewed as E, of Fig. 3. Fig. 6 is a detached, enlarged bottom end view of a terminal; and Fig. 7 indicates upon a large scale certain

constructions of the condenser members or 65 plates which may be employed and which cannot be conveniently or clearly denoted in the main figures.

R is the reaction chamber; S the resistor; V the carbon terminals; W the charge in 70 reaction; T the reserve or overhead charge; Y the hearth, and X is the zinc collector or reservoir.

The grate which forms the resistor hearth, as in Figs. 1 and 2, is formed by a series of 75 spaced refractory bars 8, while in Figs. 3 and 4 plates are employed whose upper portions serve as grate members. These bars or plates are preferably formed with sloped edges 9, and the intervening spaces 10 may 80 also be wider at their bottoms than their tops, which will facilitate the flow and clearance of inert residual matter or particles of carbon. The width of the grate spaces is to be such that normally the pieces of resistor 85 carbon will bridge them, but in any case they will serve to permit the fine ash or sintered residue, either by gravitation or by poking from above, to pass through and collect below, as in the chamber H. This also 90 permits, if desired, that dissolvent material such as lime may be fed in at intervals and the temperature of the resistor be temporarily considerably increased above the normal, whereby a viscous or semi-liquid or 95 even a liquid slag will be produced. But whether the slag is in the form of a sinter or liquefied, it may be tapped off or scraped out, as through the closable opening 12. In this wise the resistor may be operated for a 100 longer period of time than if the inert residue is collected upon a solid hearth. In fact, the operation may continue more or less indefinitely. If necessary the resistor and grate bars may readily be removed. To 105 effect this and to avoid an extreme reduction of the furnace temperature, its upper zone or a portion of it, as L, is made removable. With this off, as the reaction chamber is relatively shallow, the resistor 110 carbon, grate bars and also any residue may be rapidly removed, as by means of forks, tongs and shovels, even when quite hot. So too the heated grate can be quickly replaced and a fresh bed of resistor carbon be put 115 into position. The grate spaces also perform another function which will again be referred to. This removable zone L is readily formed by the employment of built-up refractory blocks held under right angle tension, as by means of steel channels 13 and rods 14. It also lends itself readily to the 120 formation of a series of transverse slots 15 through which the reserve charge may be fed into the reaction chamber. As shown in 125 Figs. 1 and 2, the slots are obtained by using a series of round refractory rods 16 which also serve as thrust pieces or compression

members. These may be so placed, relative to each other, as to produce openings of any desired width. Thus the material may run through freely, the slots themselves may be 5 closed by supplemental round rods, as 17, or they may be so narrow that the super-charge must be forced through by bars. In the latter instance the material will itself form a seal, as in the instance of a sand-joint. The 10 feeding-bars may be utilized to spread the reaction charge and to tamp it down into intimate contact with the resistor. The temperature of the charge and the resistor may be ascertained through these slots and any 15 collection of water vapor or CO_2 in the space above the reaction charge can readily be permitted to escape, as through a pipe or by perforating the reserve charge material at any of the said slots.

20 Figs. 3 and 4 show a modified form in which the round-rod construction is shown as substituted by molded sections 18 and the dotted outline 18* shows how a longitudinal may be introduced or substituted if desired.

25 While the reserve charge T may be maintained in a relatively deep open shaft, it is regarded advantageous not to load the resistor with an excessive supply of reacting material. The principal reasons for this are 30 that less electric current will pass through a thin than a thick charge, consequently there will be less tendency to reduce the current density and temperature in the upper surface of the resistor. Also with a 35 deep reaction charge there is a greater mass of material at some distance above the resistor, in which the temperature is not high enough to produce Zn and CO .

The carbon terminals V, instead of being 40 built into the walls of the furnace horizontally, are inserted vertically into the open ends of the reaction chamber. Relatively thin plates may thus be used and they can be readily withdrawn and replaced if desirable, concurrent with the substitution of a fresh resistor for an old one. The lower ends of the terminals may either rest upon some portion of the furnace, as 19, Figs. 2 and 4, or they may be embedded in and rest 45 upon the resistor carbon. To obtain an increased area of contact between the terminals and the resistor a plurality of wedge-like grooves or slots 20, as shown for instance in Fig. 6, are formed in their lower 50 faces. The resistor carbon is packed into these grooves, as shown in Fig. 2, with the result that the area of surface contact can readily be increased over that of a simple face-contact by from 35% to 50%. The current 55 from the bus-bars or main line cables 21 is conducted to the upper ends of the terminals by means of metallic electrodes such as copper, preferably in the form of thin wide sheets 22, their inner edges being

bent to a right angle flange 23, entering a 65 recess 24, milled along the upper ends of the said terminals. Where these electrodes pass out over the walls of the furnace they, as also the upper exposed ends of the terminals, are covered by brickwork. The inner 70 faces of the terminals, those presented toward the reaction chamber, are also sheathed by suitable removable refractory blocks or bricks 25 whereby there can be no electrical contact and no reaction set up with the ZnO 75 of the charge. Apart from the advantage already mentioned, this disposal and construction effects a practically ideal transmission of the main line power factor directly at and into the resistor bed, which is 80 a feature of prime importance when considering the somewhat complex conditions under which the furnace must be operated.

The power circuit is denoted by P, Fig. 2.

In the present scheme of condensation all 85 of the volatilized products are caused to pass from the reaction zone directly and immediately through the resistor in a vertical direction downwardly into ducts, slots, slits or spaces whose boundary surfaces progressively diminish in temperature away from 90 the resistor.

In the operation of this furnace and its integral condenser the temperature at or near to the impingement of the charge upon 95 the resistor, as in the resistor itself, is preferably maintained sufficiently high to prevent the existence of CO_2 . Moreover, as the chemically evolved volatilized products of the $\text{ZnO} + \text{C}$ reaction pass directly and immediately into and through the highly incandescent carbon of the resistor, pernicious 100 re-oxidizing mediums will be eliminated.

One manner of realizing the condenser system is shown in Figs. 1 and 2 and another 105 in Figs. 3 and 4. Either manner may be said to be a detail modification of the other, but each will be somewhat separately described. Thus in Figs. 1 and 2 the chamber H beneath the grate bars is formed by a 110 series of horizontal ship-joint plates 26, supported by ledges 27, formed in the tamped lining 28, which forms the reaction and condenser chambers. The grate bars are shown as sustained on these plates, as by means of 115 strips 29. At one end of this chamber an opening 30 is provided and the plate contiguous thereto may have a raised retaining lip or rib 31. Beneath these horizontal plates are a series of vertically disposed 120 plates, as 32, 33, supported by ledges 34 in the tamped lining. One series of plates 32 are in contact with the horizontal plates above, and the other series 33 alternating, leave a space as n above and project downwardly into the zinc receptacle, whereby the spaces are connected in series. In preliminarily starting the furnace a sufficient quan-

5 tity of molten zinc is to be introduced until the lower edges of the plates 33 are immersed therein. As a consequence the lower boundaries 10 of the spaces or galleries are formed of molten zinc. Now, what will occur is this: The zinc fume and monoxid of carbon as they leave the resistor will pass through the grate bar spaces 10 into the chamber H and thence through the opening 30 and down 15 upon the zinc bath. Continuing, as indicated by the arrows, the zinc fume and gas must thereafter alternately rise and fall, impinging upon the bath at each downward movement, until the complete circuit equal 20 to the length of the chamber is reached, from whence any residual gaseous products flow out of the condenser chamber right and left, as by the parts 35, 35^a.

25 Referring now to Figs. 3 and 4: Here the function of the grate bars is performed by a series of vertical spaced plates 35, supported by the horizontal ship-joint plates forming the chamber H, with an end opening 30, as in the former instance. Below 30 the horizontal plates are a series of vertical plates 36 having legs 37 which rest upon the bottom of the zinc receptacle and are immersed in a bath of molten zinc. These 35 plates form horizontal chambers K, the bottoms of which are zinc, part of which are connected at one end to the walls at one side of the chamber and the rest of which are connected at one end to the wall at the other side of the chamber, as in Figs. 3 40 and 5. Now, what will here take place is this: The volatilized matter and also any residual ash produced by the reaction will pass from the resistor immediately into the spaces 39, between the plates and thence to 45 the chamber H. Here the ash or sinter will remain, to be withdrawn as desired through the opening 40, but any condensed zinc, zinc fume and gas pass on through the end port 30, down upon the liquid bath of the primary chamber, winding back and forth horizontally through the tortuous course, in 50 constant contact with the bath and the surfaces of the plates, the residual gas finally leaving the condenser chamber through the ports 41, 42. The residual gas is received from the zinc receptacle ports by side chambers J, Figs. 1 and 3, which extend along and in fact "blanket" both longitudinal sides of the reaction and condensing chambers, from whence it ultimately passes, as 55 43, to mingle with the atmosphere as such or to be burned to CO₂. These side chambers perform a two-fold function, to serve if needs be as collecting chambers for "blue powder" which may be scraped out through 60 openings, as 44, and as the temperature of the gas will be relatively high, its presence in these blanketing chambers minimizes emission of heat sidewise from the hot zones

of the furnace. In this connection the 65 axiom should also be borne in mind that wherever the greatest difference of temperature exists, as between a hot and a colder body, the rate of energy flow will there be a maximum, also that the cross sectional 70 form of a heat emitting member (resistor) is a matter of prime importance. Thus to illustrate, a metallic rod-resistor of one inch diameter, having a section of .7854 square inch, would have a heat emitting surface of 75 3.1416 inches, whereas the same section in the form of a strip .05 inch thick would have a heat emitting surface of 31.5 inches. In this furnace, as is indicated in the drawings, the resistor is relatively thin to its 80 width and in practice may have a relation of from about one to five, to six, or seven; consequently only about 10 to 20% of its surface is in contact with the side walls of the reaction chamber, and 75% to 85% of 85 the surface must emit its heat above to the charge and below to the sustaining grate and the interposed spaces. It then necessarily follows that if the temperature of the volatilized products contiguous to the lower 90 surface of the resistor is high, and if the heat insulation at the sides of the resistor is good, the bulk of the energy developed in the resistor will flow where it is desired, to the relatively colder charge above. In the 95 described traverse of the fume and gas a considerable portion of the fume may be condensed in the vertical grate plate spaces, and by impingement upon the horizontal plates 26 which, if desired, may be slightly 100 sloped toward the port or opening 30. The grate bars or grate plates may preferably be of re-crystallized carborundum which is a rather good conductor of heat, but the horizontal septum formed by the plates 26 105 may preferably be of say fine clay having a less capacity for heat conduction. Consequently if, to illustrate, the temperature at the impingement of the resistor upon the grate is 2400° F. then the temperature in 110 chamber H, Fig. 4, may be about 1500° to 1600° F., while that of the septum itself would be still lower. It is to be observed that the fume and gas will considerably expand as they leave the grate spaces and 115 enter the chamber H. Beneath the septum, between it and the zinc bath, a further fall of temperature is contemplated, say to about 1200° to 1300° F., which is controllable, according to the rate of delivery of 120 fume and gas, either by circulating air or fuel heat, as the need may be, through the flues or a flue, as U, situated beneath the zinc receptacle. The tamped material forming the said receptacle is supported 125 upon a steel plate e, whereby a rapid interchange of heat may take place, as between the bath and the flue. The control of tem-

perature in the bath is a matter of importance. Where ideal conditions exist this may be automatic, as by natural conduction. But the higher its temperature, or in other words, the less difference of temperature between the bath and the resistor compatible with condensation, the greater will be the flow of heat to the charge.

The phenomenon has long been known that, as usually stated, zinc fume "condenses" most effectively when in the presence of liquid zinc. Substantially the same condensing effects will ensue if the fume is caused to flow over surfaces, between slits, across obstructions and also if rapidly and frequently changed in the direction of its flow, especially where impulsive impingements or centrifugal effects can be realized. Such conditions become the more necessary as the volume of fume relative to that of the gas is diminished.

The above conditions are realized in the circuit through which the fume and gas are caused to traverse between the septum and the bath of molten zinc. Thus, referring to Figs. 2, 4 and 5, in the furnace of ordinary capacity it is entirely feasible to obtain hundreds of reversals, forty to sixty lineal feet of traverse in contact with the bath and hundreds of square feet of plate surface contact. Moreover, any or all of the grate bars and plates may be provided with sharp ratchet-like recesses, as 47, Fig. 7, or with projecting ribs, as 48, and if these are opposed in staggered relation, as shown, the flow-area need not be reduced while a vast number of tumblings, mixings and refractions of the fume would necessarily ensue. These ribs or recesses may either be disposed obliquely or at a right angle to the flow. Such plates may easily be formed as by a molding or extruding process, and if the ribs or recesses have sharp right angle intersections with the main body of the plate, as 49, they will serve as "pockets", collecting small quantities of zinc against which the fume must impinge whatever may be the direction of flow.

As the liquid zinc accumulates it may be intermittently tapped off, as at 50, Fig. 2, or a siphoned outlet 51, Fig. 4, may be employed whereby the outflow would be continuous and the "head" be maintained at a uniform level, as indicated. The spaces beneath the bottom edges of the plates 33 and the openings 52 formed by the legs 37 of the plates 36 are to be sufficient so that by emptying the zinc chamber it may be scraped clean should such be necessary, as through the large openings 53 provided for that purpose. If the conditions are such, however they may be produced, as to sensibly obstruct the flow of the fume and gas, this will cause back pressure at and in the

reaction zone. The $ZnO + C$ reaction proceeds most effectively at or perhaps somewhat below atmospheric pressure. Moreover, when the reaction takes place under such pressure as it may proceed at, it has the contingent objectionable effect of forcing the zinc fume into the refractories. These difficulties may be overcome or minimized by the simple expedient of providing at or near to the tail end of the condensing circuit, means for producing suction, whereby obstructions to the flow such as friction-head may be partially or wholly nullified, or even "negative pressure" may be maintained at the reaction zone. Suction may be positively effected, as by the use of a vacuum pump or fan connected as at 54, Fig. 1, but as the actual friction head here to be dealt with is relatively trifling, such can be overcome by means of tubes or a tube 55 connected to the side chambers and by sufficiently extending it upwardly the effect will be similar to that of a chimney. Or a controllable withdrawal of the outgoing gas may be produced by induction. However, it is a fact that the thermal efficiency is to a considerable extent a function of the free escape of the volatile products of the reaction. Thus, for example, if the $ZnO + C$ reaction is carried on in an open crucible the utilization of the energy which reaches the seat of the reaction may be said to be a maximum, but partially close the top of the crucible and the reaction will be diminished; again close the crucible and the reaction will cease, nor will any amount of energy, ordinarily applicable, develop sufficient pressure to lift a comparatively thin, free, refractory plate. But in the maintenance of or about "atmospheric pressure" care must be taken not to cause an inflow of air to the reaction or the condenser chambers. Therefore the friction head in and at the register may be somewhat minimized by inserting free side linings, as bricks or blocks 56, Figs. 1 and 2, having numerous slits, as 57, and resting upon the resistor. In this wise, even should the resistor become somewhat clogged, as with ashy residue, there will be opportunity for free escape of the fume and gas through these side slots and thence down through those portions of the resistor which, due to the blocks, will remain free. Again, the upper surface of the resistor may be composed of a layer of broken pieces of carborundum, as 58. This will serve to establish a chain of openings across the face of the resistor and immediately beneath the most intense portion of the reaction zone; also such an interposed layer would serve to somewhat insulate the carbon of the resistor from the charge, prolonging its endurance. So, too, those portions of the resistor immediately beneath these side blocks may be formed of

8
a mixture of carbon and carborundum or of relatively small pieces of carbon, whereby to increase the electric resistance along the sides and produce a higher temperature throughout the central section of the resistor bed.

Carborundum (SiC) especially when recrystallized, is not subject to chemical attack under the above noted conditions; it is highly refractory and will endure indefinitely. It is also a satisfactory material for the tamped lining 28 and for the grate bars, grate plates and such portions of the furnace where excellent refractory quality alone, or where that quality combined with good heat conduction, are desired.

All of the grate bars or grate plates can readily be reached from the reaction chamber for examination or "poking" or for removal when the top section L is swung off, since the "reach" into the reaction chamber is quite short. Thus if the grate bars or grate plates are removed, the septum plates 26 may also be taken out, thereby exposing the underlying condenser plates whose spaces may be cleaned in place if required. Again, when the top section is removed the side chambers J may be inspected and cleaned if required.

The advantage of being able to inspect the various interior channels resides in the fact that power circuits are liable to fail and during such intervals the furnace may become sufficiently cool to produce clogging, or if the reaction capacity is beyond the liquefying capacity of the condenser and the furnace is run according to the former, then some portion of the zinc fume will be regained in the side chambers in the form of "blue powder" or as an oxidized conglomerate.

It will be apparent to those skilled in the art that various modifications, perhaps beneficial, can be made in the design and its elemental details without evasion of the spirit and essence of this invention. Thus in justification of this averment, it will suffice to point out as follows: That in the instance say of the condenser plates 32, 33, they may be disposed precisely vertical or canted in the manner shown, or a plurality of back and forth chambers could readily be built, that is, in which the flow would be in a general horizontal direction. Again, the said plates and also those shown in Figs. 3, 4 and 5 may be arranged in multiples, the flow being through a plurality of galleries; that is, in parallel instead of in series, in which case the contact surface might be the same, but the reversals and velocity of the fume and gas would be reduced. Finally, having particular reference to Fig. 4, the septum may be formed to act both as the zinc receptacle and the residue receiver, or the said

septum may even be omitted, extending the grate plates downwardly to or into the present zinc chamber. Such a modification is feasible and operative and, together with various contingent details, has had due consideration. But the advantages of using an interposed septum have appeared to warrant its employment, as for example, the surface of the zinc bath is kept cleaner and the removal of residual matter from the intermediary chamber requires a shorter suspension in the operation of the furnace than to withdraw it together with the bath from the zinc receptacle.

What I claim is:

1. In an electric zinc furnace, a grate upon which a bed-of-carbon resistor is supported, the resistor being arranged to act upon a charge when the latter is placed in the furnace.

2. In an electric zinc furnace, a bed-of-carbon resistor supported by spaced grate members forming a longitudinally extending grate underneath the same a chamber for receiving through the spaces inert residual matter, and terminals located adjacent to the ends of the grate.

3. The combination with a bed-of-carbon resistor, upon which a charge of resisting materials is sustained, of carbon terminals in whose inner faces grooves are formed, whereby an increased area of contact is provided between the broken carbon of the resistor and the said terminals.

4. The combination with a horizontal carbon resistor upon which a charge of reacting material is sustained, of vertical carbon terminals whose lower inner faces are in contact with the resistor whose outer faces are in contact with the end walls of the resistor chamber and whose upper ends are connected by metallic electrodes to the power circuit.

5. The combination with a horizontal carbon resistor, of vertical carbon terminals whose lower portions are in contact with the resistor and whose inner faces which are above the resistor are separated from the charge by insulating blocks.

6. An electric zinc furnace having a carbon resistor for receiving a superimposed charge of reacting materials, the longitudinal sides of said charge being separated from the reaction chamber walls by slotted blocks arranged adjacent to the resistor.

7. The refractory blocks disposed along the longitudinal sides of the reaction chamber and resting upon the resistor, whereby the reaction surface is of less width than the resistor.

8. The refractory blocks disposed along the longitudinal sides of the reaction chamber and resting upon the resistor, the lower portions of said blocks having openings for

- permitting a sidewise escape of fume and gas from the reaction zone.
9. The combination with the carbon resistor, of a horizontal layer of carborundum upon the said resistor.
10. The combination in an electric furnace with the reaction chamber and the resistor, of an upper removable horizontal section or zone in which the reserve charge chamber is contained.
11. The combination with a carbon resistor and a reaction chamber of a series of spaced members constituting the bottom of an overhead reserve charge chamber and providing a means through which the material in reserve may be controllably and intermittently fed down upon said resistor.
12. In an electric zinc furnace the combination with a carbon resistor and a reaction chamber, of an overhead reserve charge chamber whose bottom is provided with a series of movable spaced refractory members between which the reacting materials are fed.
13. A combined electric zinc furnace and condenser having the condensing system contained in that portion which is immediately beneath the resistor in the furnace.
14. In an electric zinc furnace, the combination with a reaction chamber, a resistor and a hearth upon which the resistor is sustained, of an underlying system of plates arranged to provide a plurality of ducts or slots through which pass the volatilized products of the reaction.
15. A zinc furnace having therein a reaction chamber, a resistor, terminals therefor and grate bars or plates for sustaining the resistor, said bars or plates disposed to form vertical slits or spaces to permit the flow of the volatilized and also the inert residual products of the reaction from above so that they may be discharged in an underlying chamber or receptacle.
16. In a combined electric furnace and condenser a series of condenser members located beneath the resistor and arranged to provide slits or slots therebetween.
17. The combination with the reaction chamber, a resistor therein for operating upon a charge when placed in the chamber and a spaced sustaining grate, of an underlying chamber for receiving the products of the reaction.
18. In an apparatus for use in the metallurgical processes, the combination of a resistor of an electric furnace, a sustaining hearth therefor, and beneath said resistor a member providing a chamber from which the inert products of the reaction may be removed through an opening or openings in a wall of the member.
19. In an apparatus of the class described the combination of a resistor, a section ad-
- jaacent to and beneath the resistor, which section constitutes the condenser, and an underlying receptacle for containing and collecting liquid zinc.
20. In an apparatus comprising an electric furnace of the resistor type, and a fume condenser, means providing a resistor hearth, a refractory septum disposed between the resistor hearth and a zinc receptacle, there being a passageway which permits any or all of the products of the reaction to flow from the reacting zone to the condenser and which also permits at least a part of said products to pass at least a part of said septum.
21. A section adjacent to and beneath the resistor of an electric furnace, said section containing a condensing system, in combination with an underlying receptacle for receiving the liquidized, the liquefied and the gaseous products of the reaction.
22. A condensing system disposed beneath the resistor, of an electric furnace, said system having spaced members, the lower ends of at least part of which extend into a bath of liquid zinc.
23. A combined furnace and condenser having a port or ports leading from a zinc receptacle in the lower part of the condenser, there also being provided longitudinal chambers, at least part of which are located in the furnace walls and into which chambers the residual gaseous product of the reaction primarily passes, and from whence it passes to the atmosphere.
24. In an electric zinc furnace provided with a condenser, the combination with a bed of carbon resistor, upon which a charge of reacting materials is sustained, passageways for evacuating the volatilized products of the reaction, and means for producing suction, whereby to approximately maintain atmospheric or negative pressure at the reaction zone.
25. An electric zinc furnace having a receptacle for receiving liquid zinc and provided with a flue or flues disposed beneath said receptacle for the purpose of controlling the temperature in the receptacle.
26. Condensing members such as plates, bars, blocks or the like for use in apparatus for condensing zinc fumes, provided with recessed or raised portions.
27. A condenser having plates, bars, blocks or the like, provided with recessed or projecting portions that are disposed obliquely to the flow of the volatilized products of the reaction.
28. In a condenser, plates, bars or blocks which are provided with sharp recesses or ribs disposed at an angle to the flow of the volatilized products of the reaction.
29. Condenser plates, bars or blocks provided with recesses or ribs and arranged so

that the facing recesses or ribs of adjacent members are in staggered relation to each other.

30. Electric furnace grate bars or grate plates whose upper edges are sloped and upon which the resistor of the furnace is sustained.

This specification signed and witnessed this 31 day of December A. D. 1912.

JOHN THOMSON.
